CLAIM

The ornamental design for a pillow, as shown and described.

DESCRIPTION

FIG. 1 is a perspective view of a pillow showing my new design.
 FIG. 2 is a left side elevational view of the pillow.

FIG. 3 is a right side elevational view of the pillow.

FIG. 4 is a rear elevational view of the pillow.

FIG. 5 is a front elevational view of the pillow.

FIG. 6 is a top plan view of the pillow in a closed configuration.

FIG. 7 is a bottom plan view of the pillow in a closed configuration.

FIG. 8 is a top plan view of the pillow in an open configuration; and,

FIG. 9 is a bottom plan view of the pillow in an open configuration.

The broken lines in the figures depicting portions of the pillow form no part of the claimed design.
